(57) CLAIM

We claim the ornamental design for a knob for a cookware lid, as shown and described.

DESCRIPTION

FIG. 1 is perspective view of the knob mounted on a cookware lid that is covering a cooking vessel, with the thermometer probe removed;

FIG. 2 is a top view of the knob showing the slide in a closed position;

FIG. 3 is a top view of the knob showing the slide in an open position;

FIG. 4 is an elevational view of the knob taken from the right side of FIG. 2;

FIG. 5 is an elevational view of the knob taken from the left side of FIG. 2;

FIG. 6 is a side view of the knob; the other side is a mirror image.

The ornamental design which is claimed is shown in solid lines in the drawings.

The broken lines in the drawings show environmental structure.
